(57) **CLAIM**

The ornamental design for a winged atraumatic trocar for pellet insertion as shown and described.

DESCRIPTION

FIG. 1 shows an isometric view of a winged atraumatic trocar for pellet insertion in a disassembled state for clarity of disclosure, with the winged cannular component positioned adjacent to the winged obturator.

FIG. 2 shows a second isometric view of the winged atraumatic trocar for pellet insertion shown in its fully assembled state.

FIG. 3 shows a side view of the winged atraumatic trocar for pellet insertion shown in its fully assembled state; and,

FIG. 4 shows a top view of the winged atraumatic trocar for pellet insertion shown in its fully assembled state.
